UNITED STATES PATENT OFFICE.

CHARLES H. YARRINGTON, OF CHESHIRE, CONNECTICUT, ASSIGNOR TO THE
CHESHIRE WATCH COMPANY, OF SAME PLACE.

MANUFACTURE OF WATCH-CROWNS.

SPECIFICATION forming part of Letters Patent No. 351,085, dated October 19, 1886.

Application filed March 3, 1886. Serial No. 193,837. (No model.)

To all whom it may concern:

Be it known that I, CHARLES H. YARRINGTON, of Cheshire, in the county of New Haven and State of Connecticut, have invented certain new and useful Improvements in the Manufacture of Watch-Crowns, of which the following is a full, clear, and exact description, whereby any one skilled in the art can make and use the same.

10 My invention relates to the processes by which watch-crowns as specific articles are produced, and also to such steps in the art as relate to the attachment of the crown to the winding-spindle adapted for use in a watch.

15 The object of my improvement is to provide such articles in a cheap and durable form by the use of dies; and my improvement consists in the method of forming a watch-crown from a single piece of metal that is stamped, drawn, 20 corrugated, and formed by the several steps, as more particularly hereinafter described, and pointed out in the claims.

Referring to the accompanying drawings, Figure 1 shows both an edge and plan view of 25 the circular blank from which the crown is formed. Fig. 2 is a detail view in central vertical section of the dies, between which the blank is formed in the second step in the process of forming the crown. Fig. 3 is a detail 30 edge view of the crown-blank, showing the product of the second step in the method. Fig. 4 is a detail view in vertical section of the cupping-dies used in the third step in the method. Fig. 5 is a view in vertical central 35 section of the cup-shaped blank, which is the product of the third step. Fig. 6 is a detail sectional view of the crown-corrugating dies used in the practice of the fourth step in the process. Fig. 7 shows in side elevation and 40 in plan view the crown-blank after it has been corrugated. Fig. 8 is a detail view in central section of the crown-blank after the nipple has been bored and a thread tapped to receive the threaded end of the winding-spindle, 45 this being the modified form of fastening the crown to the stem. Fig. 9 is a detail side view of the crown and stem after the crown has been formed to final shape and the edge milled to fit the stem of the watch. Fig. 50 10 is a detail view in central section of a crown,

showing a spring-base and spring in the modified form of fastening the crown to the stem. Figs. 11 and 12 are views in central section of the watch-crown, showing a stem with upset end and a stem-socket in the crown, illustrating the means of securing the crown to the stem. 55

In the drawings, the letter *a* denotes a disk-shaped blank cut or punched from a sheet of metal of proper thickness by any ordinary 60 method and means; *b*, a nipple left in reducing the edges of the blank *a*, forming finally the thick base *c* of the crown; *d*, the sides of the crown; *e*, the winding-spindle; *e'*, the end of the spindle that is adapted to fit the socket 65 *f*, which is made in the inner surface of the base of the crown.

The blank is provided during the process of its formation with a central indentation or the drill-guide, *b'*, in the surface of the nipple, 70 and on the reverse or outer surface with a centering-mark, *b''*, these guide-marks being preferably made by a central projecting point or punch in the recess of the female dies.

The blank *a* having been cut or punched 75 from a sheet of metal as the first step in the process of making the crown, is next subjected to the action of the dies *g* and *g'* in the second step in the process, the socket in the female die *g'* having preferably the central punch, *g''*, 80 that forms the drill-guide *b'* in the nipple *b*, the edges of the blank in this operation being greatly reduced in thickness on all sides of the central nipple that is left at substantially the full thickness of the blank *a*. In the next 85 step of the process the blank, after having had the thin edges trimmed on a circle struck from the center of the base, is subjected to the process of the cupping-dies *h* and *h'*, the bottom of the punch having a recess into which the nipple *b* fits and thus centers the work and holds it while the edges are drawn and shaped. The thin edges of the blank are by this process bent and drawn to the cup shape shown in 90 Fig. 5, the crown-blank now having the thick base *c* and thin sides *d* approximating the final form. The sides *d* are still further thinned out by the action of dies and the edge of the blank is again trimmed, as by turning or grinding, 95 and is next crimped by the dies *i* *i'*, thus 100

forming the corrugated cup-shaped crown with the sides still flaring slightly outward, as shown in Fig. 7. The socket *f* is next drilled in the inner side of the base, the guide-mark 5 aiding in centering the drill, and into this socket the end *e* of the winding-spindle *e* is fitted. The next step in the process consists in closing the metal of the base firmly upon the end of the spindle when it is not threaded, 10 and in curving the edges of the sides of the crown inward near the edge toward the spindle, producing the globular form shown in Fig. 9.

I do not confine myself to the angular or up-set ends and compression of the nipple as a 15 means of engaging the winding-spindle in the socket *f*, but may make use of any equivalent and ordinary means, as a screw-thread on the stem and a threaded socket in the nipple, as 20 shown in Figs. 8 and 10, for the purpose of securely fastening the crown and spindle together, as described.

As a final step, the edge of the crown is milled or turned out on its inner side on a 25 curved plane parallel to and equidistant from the spindle, so that it will fit snugly about the stem of the watch while the spindle passes through an opening in the stem, as illustrated in Fig. 9.

30 In order to adapt the spindle and crown to a particular form of watch-movement in connection with which the spindle has a sliding and a rotary motion also in the stem and is held outward by a spring, an annular collar, 35 *k*, is fitted upon the inner end of the stem, resting against a shoulder, as at the base of the thread. When the spindle is secured to the crown, the collar is tightly held between the shoulder and the base and forms a broad rest 40 to take the thrust of the spring.

The article substantially as herein shown and described forms the subject-matter of another application filed by me in the Patent

Office, and the following claims are to the method or process only.

I claim as my invention—

1. The improvement in the art of making watch-crowns, which consists, first, in reducing the edges of a circular blank, leaving the center the full thickness of the blank to form a 50 base at the center of the crown; secondly, in drawing out said edges and curving them upward to form the sides of said crown; thirdly, in corrugating the sides of the crown; fourthly, in drilling a hole in the base to receive the end 55 of the winding-arbor, and, fifthly, in closing the metal of the base about the spindle end, whereby the crown is firmly secured upon the arbor, all substantially as described.

2. The improvement in the art of making 60 watch crowns, which consists in blanking out a disk of metal of suitable size, indenting it upon its under side, whereby a guide-mark is formed to aid in the subsequent process, reducing said blank at its edges, leaving the center to form a base, then drawing said edges, curving them upward and corrugating them, then drilling the base to receive the end of the winding-arbor, and, finally, closing the 70 metal of the base upon the end of the winding-arbor, whereby the crown is firmly secured upon the arbor, all substantially as described.

3. The method of making watch-crowns, which consists in reducing the edge of a metal disk in dies, leaving the center to form a base, 75 drawing, curving, and corrugating said edge, drilling the base to receive a locking device on the end of the winding-arbor, closing the metal of the base upon the arbor end, closing the edge of the crown inward, and then milling 80 out the center to fit the watch-stem, all substantially as described.

CHARLES H. YARRINGTON.
